BRUSH AND SCRAPER FOR BOOTS

Paul Staheli, Arvida, Quebec, Canada

Application June 9, 1945, Serial No. 598,572

2 Claims. (Cl. 15—112)

1

This invention relates to improvements in shoe cleaning devices and the object is to provide an efficient device of this nature which is of pleasing appearance and is designed to eliminate sharp edges or corners likely to cause injury to the users thereof.

The foregoing and other objects of the invention are attained by certain novel features and combination of features as set forth in the following detailed description of the accompanying drawings, in which—

Fig. 1 is a top plan view of a shoe cleaning device having the component parts designed and assembled in accordance with my invention.

Fig. 2 is a front elevation of the assembly shown in Fig. 1.

Fig. 3 is a rear elevation of the assembly shown in Fig. 1.

Fig. 4 is a side elevation of the assembly shown in the preceding figures.

Fig. 5 is a vertical sectional view taken along the line 5—5 of Fig. 3.

Fig. 6 is a view similar to Fig. 5 but showing an element of the assembly in a different position.

Fig. 7 is a fragmentary sectional view taken substantially along the line 7—7 of Fig. 1 with the right hand brush omitted.

Referring more particularly to the drawings, 5 designates a pair of side members adapted to be secured to a supporting structure A, such as a porch step or floor, by screws 6 passing downwardly through attaching flanges 7 extending outwardly from the lower ends of said members.

Members 5 constitute the side walls of a substantially V-shaped dirt-receiving trough 9, the inclined front and rear walls of which are respectively indicated at 10 and 11. The wall 10 is formed by a stationary inclined plate positioned between and supported by the members 5. The upper edge of wall 10 projects forwardly a slight distance beyond the members 5 and is formed with a thickened portion 10a which is covered by a sheath 10b of rubber or other suitable material, the outer surface of said sheet being preferably formed with longitudinally extending ribs 10c. The lower edge of wall 10 projects a slight distance rearwardly beyond the members 5 to provide a lip extension 10d beneath which a dust pan may be inserted. The rear wall 11 of trough 9 is formed by a movable plate which is normally positioned, as shown in Figs. 1, 3, 4 and 5, with its lower edge resting on the upper surface of the front wall 10 above the lip 10d. The lower edge of wall 11 is thickened as indicated at 11a and is provided with downwardly directed pins

11b which are received in holes 10e provided in wall 10. The end edges of wall 11 are provided with outwardly extending trunnions 11c located relatively close to the upper edge of said wall. 5 These trunnions provide pivot bearings for wall 11 and work in V-shaped slots 13 provided in rearwardly projecting brackets 14 carried by the members 5. Each slot 13 is arranged so that the ends 13a and 13b provide upper and lower bearings for the trunnions 11c working therein. The wall 11 is normally arranged with the pins 11b engaged in the holes 10e and the trunnions 11c engaged in the lower bearings 13b.

When it is desired to clear the trough 9 of the 15 mud and dirt accumulating therein, the wall 11 is raised in a plane perpendicular to wall 10 to lift the pins 11b clear of holes 10e and to elevate the trunnions 11c clear of their bearings 13b. The trunnions 11c are then positioned in their upper 20 bearings 13a and wall 11 is then swung upwardly and rearwardly to the out-of-the-way position shown in Fig. 6, thus providing a discharge opening B through which the mud and dirt accumulating on the upper surface of wall 10 may be removed into a dust pan inserted beneath the lip extension 10d of said wall.

In the present instance the plate-forming wall 10 is shown as a separately formed plate fastened by screws 10f to supporting shoulders 5b provided by thickened portions of members 5. It will be understood, however, that wall 10 may, if desired, be cast as an integral part of members 5

A scraper bar 15 extends longitudinally above the trough 9 and has its ends fitted in supporting openings 15a (Fig. 7) provided in the upper portions of members 5. In the present instance the scraper bar is welded in place as indicated at 16 but it will be understood that it may, if desired, be detachably secured in place in any desired manner.

The portions of members 5 extending above the scraper bar are formed to provide brush housings 17 in which brushes 18 are detachably secured. As shown more clearly in Fig. 7, each brush 45 18 includes a head or backing member 19 to which bristles 20 are secured so that the bristles incline downwardly toward the scraping edge of the scraper bar 15 when the brush is secured in place. The head or backing member 19 of each brush 50 is provided with a threaded socket 21 into which is screwed the inner end of a brush retaining bolt 22 which is passed into the brush casing 17 from the outer side of member 5. Each bolt 22 is provided with a head 23 at its outer end and is also provided intermediate its length with a

retaining collar 24 which works in a recess 25. The collar 24 prevents the bolt 22 from being completely detached from the member 5 with which it is associated. The brushes 18 are firmly secured in place within the brush housing when the bolts 22 are threaded into the sockets 21 until the heads of the bolts are engaged with the outer sides of members 5 with the brush heads 19 drawn tightly against the outer side walls of the brush housings 17.

In using the device described herein the user moves the bottom portion of his shoe back and forth across the upper edge portion of the scraper bar exposed between the brushes 18 which serve to clean the side portions of the shoe. The mud and dirt thus removed from the bottom and side portions of the shoe drop into the trough 9 and are deposited on the upper surface of the stationary wall 10. This mud and dirt is trapped in the trough 9 when the wall 11 is positioned as shown in Fig. 5 but is easily removed therefrom when wall 11 is transposed to the position shown in Fig. 6 to provide the discharge opening E through which the mud and dirt are brushed or scraped into a dust pan positioned beneath the lip extension 10d.

Having thus described what I now conceive to be the preferred embodiment of this invention it will be understood that various modifications may be resorted to within the scope and spirit of the appended claims.

I claim:

1. A shoe cleaning device comprising side walls, a scraper blade supported between the upper portions of said walls and at a substantial distance from their front and rear edges, an inclined plate underlying said scraper blade and connecting said walls, the width, inclination and placement of said plate being such that its front edge is considerably higher than its rear edge and is located close to the front edges of the side walls at a substantial distance above the lower edges of said walls, the rear edge of said plate being positioned

close to the rear and lower edges of said walls and a second movable plate having its lower edge normally supported on the rear portion of the first mentioned plate to form with the latter an open top V-shaped dirt-receiving trough, said second plate being provided with trunnions fitted in slots formed in the rear portions of the side walls, said slots being shaped so as to provide, in conjunction with said trunnions, a plate mounting means whereby the movable plate is mounted for movement in a plane perpendicular to the upper surface of the first mentioned plate and also for swinging movement about a horizontal axis.

2. A shoe cleaning device as set forth in claim 1, in which the lower edge of the movable plate is provided with downwardly projecting pins receivable in openings provided in the first mentioned plate to support the movable plate in trough-forming relation to the first mentioned plate.

PAUL STAHELI.
